CLAIM

The ornamental design for a light therapy device, as shown and described.

DESCRIPTION

FIG. 1 is a frontal perspective view of an embodiment of a design for a light therapy device;

FIG. 2 is a front view of the light therapy device shown in FIG. 1;

FIG. 3 is a rear view of the light therapy device shown in FIG. 1;

FIG. 4 is a first side view of the light therapy device shown in FIG. 1;

FIG. 5 is a second side view of the light therapy device shown in FIG. 1;

FIG. 6 is a top view of the light therapy device shown in FIG. 1;

FIG. 7 is a bottom view of the light therapy device shown in FIG. 1;

FIG. 8 is a rear view of the light therapy apparatus shown in FIG. 1 with an embodiment of a design for a support post within a receptacle a back side of the light therapy apparatus;

FIG. 9 is a side view of the light therapy apparatus of FIG. 1 supported by the support shown in FIG. 8; and,

FIG. 10 is a rear perspective view of the light therapy device shown in FIG. 1, supported by the support shown in FIG. 8.

The broken lines shown in the drawings represent unclaimed structure behind the panel and form no part of the claimed design.
